UNITED STATES PATENT OFFICE.

ABNER D. DAILEY, OF RILEY, INDIANA.

HARVESTING AND SIMILAR MACHINES.

SPECIFICATION forming part of Letters Patent No. 245,455, dated August 9, 1881.

Application filed February 18, 1881. (No model.)

To all whom it may concern:

Be it known that I, ABNER D. DAILEY, of Riley, in the county of Vigo and State of Indiana, have invented a new and useful Improvement 5 in Harvesters and Similar Machines, of which the following is a full, clear, and exact description, reference being had to the annexed drawings, forming part of this specification.

10 The object of my invention is to provide a self-acting rest or support for the tongue of a harvester or similar machine, whereby the necks of the animals drawing the machine shall be relieved of the increased weight which 15 is thrown upon the tongue when the machine comes to a stand.

The invention consists in a vertically-oscillating support, which is adapted to assume a perpendicular position when the forward end 20 of the tongue is slightly elevated, and thus support the weight of the tongue when the machine is brought to a stand, and to be thrown backward out of the perpendicular position when the machine is set in motion, in order to 25 allow the forward part of the machine to come sufficiently near the ground to accommodate the sickle-bar.

In the accompanying drawings, Figure 1 is a perspective of the frame-work of a two-wheeled 30 machine with my improvement attached, and Fig. 2 is a sectional side elevation of the same.

It is well known that reapers and mowers which are supported upon two wheels are adapted to balance themselves when in motion 35 with a comparatively-slight pressure upon the tongue; but as soon as such a machine comes to a stand the weight of the tongue alone is sufficient to cause the machine to tilt forward and throw a large proportion of its 40 weight upon the tongue, and thus upon the necks of the horses. Now, as a rigid support for the tongue would need to be very short in order to allow the forward part of such a machine to assume its proper position when in operation, it is evident that such a support would 45 not be long enough to elevate the tongue when standing so as to relieve the horses of the superadded weight. I have therefore constructed an oscillating support, A, which is 50 adapted to be pivoted to the tongue of a ma-

chine in such manner that when the tongue is slightly elevated, as always happens when the momentum of the machine is checked by reining up the horses, it will, by force of gravity, assume a perpendicular position, and 55 when the machine is drawn forward the lower end of the support, by its contact with the ground, will be thrown backward out of the perpendicular position, so as not to interfere with the proper action of the machine. This 60 support consists of a bar of wood or metal having a vertical series of perforations, by which it may be adjusted to suit the height of different machines, and having the forward portion of its lower end beveled, and, when made of 65 wood, provided, in addition thereto, with a metal plate.

The support A is pivoted to one side of the tongue B, near the rear end thereof, by means of a curved bar or bracket, C, which is secured to the same side of the tongue, and a suitable bolt passing through the bracket, the support, and the tongue. The opening for the support thus formed between the tongue and the bracket is made sufficiently elongated in 70 the direction of the tongue to allow the support to oscillate far enough to the rear to be entirely without effect upon the operation of the machine when the latter is in motion.

The bevel or rearwardly-inclined plate at the 80 lower end of the support is designed to lessen friction as the said end trails lightly upon the ground, and as the extreme point of the support is thus made sharp it is the better enabled to hold its perpendicular position when 85 the tongue is elevated and the machine at rest.

It will readily be seen that the device above described is self-acting, and that it assumes its operative position invariably when the forward end of the tongue is elevated without in 90 the least interfering with the proper action of the machine when the latter is in operation.

Having thus described my invention, what I claim as new, and desire to secure by Letters Patent, is—

In a harvester or similar machine, the combination of the tongue B, the bracket C, secured to one side thereof and therewith forming an elongated opening, and the oscillating support A, having a vertical series of perfora- 100

tions, by which it shall be adjustably pivoted in said opening, and a beveled plated lower end, which is adapted to assist in holding the support in a perpendicular position when the 5 machine is at rest or to trail upon the ground when the machine is in motion, substantially as shown and described.

In testimony whereof I affix my signature in presence of two witnesses.

A. D. DAILEY.
